Application February 28, 1938, Serial No. 193,112

3 Claims. (Cl. 250—20)

This invention relates generally to radio receiving equipment, and particularly equipment adapted for use with radio waves of ultra high frequencies, as for example from 30 to 60 megacycles. More particularly it relates to that part of the radio receiver including the detector and audio frequency amplifiers interposed between the detector and a loud speaker or like translator.

It is an object of the invention to provide a receiver of the above character which will be characterized by quietness of operation, without sacrifice of selectivity or sensitivity. By quietness of operation I have particular reference to absence of parasitic noises such as are frequently experienced in such systems, freedom from local alternating current hum, and comparative freedom from so-called diathermic interference. By diathermic interference I have particular reference to interference caused by various pieces of high frequency equipment, such as medical units.

A further object of the invention is to provide a novel form of resistance coupling to the input of an audio frequency amplifier, whereby parasitic and interfering noises are suppressed.

Further objects of the invention will appear from the following description in which the preferred embodiment of the invention has been set forth in detail in conjunction with the accompanying drawing.

The present invention makes use of resistance coupling to the input of an audio frequency amplifier, and this coupling is such that certain types of interfering impulses are suppressed. Generally it is convenient to make use of this form of coupling between the output of the radio frequency detector, and the input of the first stage of audio frequency application. The same type of coupling can be used in subsequent stages of audio frequency application, and as will be presently pointed out, a limiter network or repeater can be interposed between successive stages.

Referring now to the circuit diagram constituting the single figure of the drawing, it illustrates a radio receiver consisting generally of a radio frequency amplifier 10, a detector or demodulator 11 and a stage 12, of audio frequency amplification having its input coupled to the output of detector 11. Following the audio frequency amplifier 12 there is a limiter network 13, and this network supplies the last stage audio frequency amplifier 14. In a conventional system a loud speaker 16 is coupled to the output of the amplifier 14.

The type of detector 11 illustrated makes use

of a twin diode electron relay 17. This tube makes use of the two anodes 18 and 19, and the two heated cathodes 21 and 22. The input circuit includes the inductance 23 which is tuned by the variable condenser 24, and has its one side connected to the anode 18, and its other side connected to the cathode 21, through the condenser 25. Cathode 21 is shown connected to ground, through the by-pass condenser 26, and the biasing resistor 27. Anode 19 is connected to ground, while cathode 22 is connected by conductor 28, to the two resistors 29 and 30, which in turn connect respectively to one side of inductance 23, and the cathode 21. The heater or heaters for cathodes 21 and 22 are supplied with current from some convenient source, as is well known to those skilled in the art. One side of the heater circuit can be grounded as illustrated. To supply a suitable source of B-battery potential to the detector 11, a resistor 31 connects between the cathode 21 and the B-battery or plate supply bus conductor 32.

A detector of the type described above will effectively integrate or de-modulate radio signal energy, and because of its stability it is particularly desirable with ultra high frequencies of the order mentioned.

The audio frequency amplifier 12 includes an electron relay 33 of the triode type, having a plate or anode 34, a grid 35 and a cathode 36. The input circuit for the amplifier 12 and the coupling between this input circuit and the output of the detector 11, is preferably as follows: A pair of resistors 37 and 38, are serially connected together, and are of exactly the same value. The end terminal of resistor 37 connects to the grid 35, and the end terminal of resistor 38 connects to ground, as for example to the grounded bus conductor 39, which may be the frame or chassis of the set. The cathode 36 is also connected to ground through the resistor 41, which is shunted by the by-pass condenser 42. Serially connected between the cathode 22 of the detector 11, and the mid-point 43 between resistors 37 and 38, are the blocking condenser 44 and the variable resistor or potentiometer 46. The precise manner in which this input circuit for the amplifier 12 and the coupling afforded to the detector, operate to suppress noise, will be subsequently described in detail.

The limiter network 13 makes use of a multi-grid electron relay 48, having the plate or anode 49, grids 50, 51 and 52, and heated cathode 53. The input circuit and the coupling between the input circuit of the network 13 and the output

of audio frequency amplifier 12, is entirely non-inductive, and can be constructed as follows: Plate 34 of relay 33 connects to the plate 49 of the limiter relay, through the blocking condenser 56 and resistor 57. Plate current for the amplifier relay 33 is applied from the bus conductor 32, through the resistor 58. A network of resistors 59, 60, 61 and 62 connect with the grid 52. Thus as illustrated one terminal of the resistor 59 connects between condenser 56 and resistor 57, while the other terminal connects to the resistors 60 and 61. Resistor 61 connects to the grid 52, while resistor 60 connects to the grounded bus conductor 39. Resistor 62 connects directly between grid 52 and the bus conductor 39.

The plate circuit for the limiter relay 48 includes the resistors 64 and 65 which are connected in series between plate 49 and the B-battery bus conductor 32. Grid 51 also connects between resistors 64 and 65, and to ground through the resistor 66. The grid or suppressor 50 is shown conductively connected to the cathode 53, and both these elements are connected to ground through conductor 67.

The audio frequency amplifier 14 includes the electron relay 68, of the pentode type, which has an anode or plate 69, grids 70 and 71, and heated cathode 72. For coupling the input of this amplifier to the output of the limiter network 13, a pair of resistors 73 and 74 are provided, which serially connect between the grid 71, and ground. These resistors are of equal value, and the connection between the same is connected to the plate 49 of the limiter relay 48, through the blocking condenser 76. The cathode 72 is connected to ground through the biasing resistor 77, which is shunted by the by-pass condenser 78.

Assuming that the last amplifier 14 operates a loud speaker 16, the plate circuit of relay 68 can include the transformer 79, the secondary of which is connected to the loud speaker 16.

The proper values for the resistors employed will depend upon various circuit characteristics, and the characteristics of the electron relays employed. As previously pointed out the resistors 37 and 38 should be of equal values, and this is likewise true of the resistors 59, 61, and 62 of the limiter network 13, and the resistors 73 and 74 of the audio frequency amplifier 14.

By way of example, the various resistors can have specific values as follows: Referring first to the detector 11, resistors 29, 30 and 31 have values of about 50,000 ohms, 0.5 megohm, and 50,000 ohms respectively. The biasing resistor 27 can be of the order of 10,000 ohms. With respect to the audio frequency amplifier 12, and its coupling to the output of the detector 11, resistors 37 and 38 can each be of the order of 0.1 megohm. Pottentiometer 46 can have a range of resistance from zero to a maximum of about 1.0 megohm. Biasing resistor 41 can be of the value of about 1,000 ohms. Series resistors 59 and 60 carrying plate current to relay 33, can be of the order of 50,000 and 20,000 ohms respectively. With respect to the network 13 and its coupling to amplifier 12, resistors 61 and 62 can each be of the order of 50,000 ohms. Grid resistor 57 can be of the order of 50,000 ohms. Resistors 64 and 65 in the plate circuit of relay 48 can be of the order of 10 megohms and 50,000 ohms respectively. Resistor 66 can be of the order of 6,000 ohms. With respect to the last amplifier 14 and its coupling to the output of network 13, resistors 73 and 74 can each be of the value of 1 megohm.

Biasing resistor 77 can be of the value of 450 ohms.

Proper values for the various by-pass condensers will be understood by those skilled in the art. For example the by-pass condenser 25 for the detector 11 can be of the order of .0001 microfarad. By-pass condenser 26 of the order of 0.1 microfarad. Coupling condenser 44 can be of the order of 0.1 microfarad, and by-pass condenser 42 for the audio frequency amplifier relay 10 33, about 10 microfarads. Coupling condenser 56 can be of the order of 1 microfarad, and coupling condenser 76 about 0.01 microfarad. By-pass condenser 78 for the last amplifier relay 15 15 can be about 10 microfarads.

The B-battery source for the various relays can be a battery, but in most instances will consist of a rectifier 81, operating from alternating current supply lines, together with a filter 82.

Operation of the system described above, can 20 be outlined as follows: De-modulated or integrated signal energy from the detector 11 is impressed upon the grid 35 of the audio frequency amplifier 12, through the coupling condenser 44, the variable resistor 46 and resistor 37. Amplified and corresponding current variations in the output of amplifier 12, are repeated through the limiter network 13, and impressed upon the grid circuit for the final audio frequency amplifier 14. The variable resistor 46 constitutes a volume control, whereby the intensity of current variations applied to the amplifier 12 can be adjusted over a wide latitude, thus adjusting the sound level of the loud speaker 16 for signal energy of a given strength.

In operating a radio receiver upon ultra high frequencies, as for example from 30 to 60 megacycles, so-called diathermic interference is always a troublesome factor. Medical and other high frequency units operate generally within 40 this range of frequencies, and frequently such equipment is not properly designed, or properly shielded to prevent radiation. It is typical of such interference that it is modulated by a 60 cycle hum, and with the usual type of ultra high 45 frequency radio receiver, this hum will cause interference over a relatively wide range of frequencies, and will drown out reception of a desired signal. According to my observations this type of interference is due to a large measure to 50 the fact that the audio frequency amplifier of such receivers are not only sensitive to pulsations of the desired signal energy, but are also unduly sensitive to interfering impulses such as cause or accompany noisy reception as described above. 55 Interference of the type which I particularly desire to nullify or suppress, appears to be characterized by a distortion of the audio frequency wave form, and this has the effect of making the amplifier system extremely noisy over a relatively 60 wide band of frequencies. Even though the interfering frequency may not of itself be relatively broad, the noise produced in the loud speaker can be had over a relatively wide range of tuning, thus making it difficult if not impossible to 65 properly receive signals above the noise level.

Referring now to the amplifier 12, since resistors 37 and 38 are equal in value, potentials applied from the output of detector 11, to point 43, whether positive or negative in sign, divide 70 equally between the resistors 37 and 38. Although resistor 38 is connected to what is normally a point of neutral potential, momentary interfering impulses of the type referred to above cause momentary shift in the potential applied 75

to the cathode 36, because of the connection of this cathode to the grounded bus conductors 39 through resistor 41. Thus for such momentary interfering impulses, the momentary potential difference between cathode 36 and grid 35 is such as to not cause a corresponding current variation in the plate current. In other words with this amplifier the signal energy on the positive side of the cycle is properly impressed upon the grid 35 to cause corresponding amplifier current variations in the plate circuit. However, abnormal interfering potential variations such as cause noisy reception with a 60 cycle hum are nullified. With respect to the suppressor 13, the relay 48 and the input and output circuits connected to the same, are designed to limit the maximum intensity of impulses repeated to the input circuit of the final amplifier 14. The audio frequency amplifier 14 because of the equal resistors 73 and 74, likewise serves to minimize the noise and interference of the type previously described.

Because of the action described above, the noise level produced by diathermic machines is greatly lowered without lowering the sensitivity of the receiver to radio signal energy. At the same time such interference is relatively sharply localized upon the tuning dial, so that radio signal energy of a frequency not far remote from the principal frequency of the interference, can be tuned in without difficulty.

The limiter network 13 can be omitted if desired, in which event the output of amplifier 12 can be directly coupled to the input of amplifier 14. However, as previously pointed out the limiter network is desirable in suppressing momentary potential impulses, which would otherwise be of relatively high intensity compared to the signal impulses. Briefly, this limiter network operates as follows: Normally the plate cathode impedance of relay 48 is relatively high, for the desired signal energy. When an interfering impulse of considerable intensity, greater than that of the signal energy, is impressed upon grid 52 through resistor 61, the plate cathode potential is immediately lowered to a relatively low value, during the duration of the impulse, whereby such impulse is not effectively repeated to the input of the last relay 14.

I claim:

1. In a radio receiver, a detector of radio frequency signals, an audio frequency amplifier, said amplifier including an electron relay having anode, grid and cathode elements, and means forming a noise suppressing resistance coupling

between the output of the detector and the input of the amplifier, said means including a pair of grid resistors connected in series between the grid and ground, a biasing resistor connected between the cathode and ground, the first mentioned pair of resistors being of equal values, and a connection to the mid-point between the resistors from the output of the detector, for applying potentials from the detector to the amplifier. 5

2. In a radio receiver, a detector of radio frequency signals, an audio frequency amplifier, said amplifier including an electron relay having anode, grid and cathode elements, and means forming a noise suppressing resistance coupling 15 between the output of the detector and the input of the amplifier, said means including a pair of grid resistors of equal values connected in series across the grid and ground, a biasing resistor connected between the cathode and ground, and 20 means forming a connection between the output of the detector and the mid-point between the first named resistors, for applying potentials from the output of the detector to the amplifier, said last means including in series with the same 25 a variable resistor and a blocking condenser.

3. In a radio receiving system, a radio frequency detector, an audio frequency amplifier, said amplifier including an electron relay having anode, grid and cathode elements, noise suppressing means serving to couple the output of the detector to the input of the amplifier, said last means including a pair of resistors each of equal value connected in series across the grid and ground, a resistor connected between the cathode and ground, and a connection between the output of the detector and the mid-point between the first two named resistors, said connection serially including a blocking condenser and a variable resistor, a limitor network 40 having its input coupled to the output of the audio frequency amplifier, a second audio frequency amplifier, and a noise suppressing coupling between the input of the last named amplifier and the output of the limitor network, said 45 last named means including a pair of resistors of equal value connected in series between the grid of the last mentioned relay and ground, a resistor connected between the cathode and ground, and a connection including a blocking condenser between the output of the network and the midpoint between the resistors of equal 50 value.
